UNITED STATES PATENT OFFICE.

SAMUEL N. ACKER, OF WASHINGTON, DISTRICT OF COLUMBIA.

DESIGN FOR A MEDALLION, BADGE, WATCH-FOB, OR SIMILAR ARTICLE.

47,480.

Specification for Design.

Patented June 22, 1915.

Application filed May 14, 1914. Serial No. 838,585. Term of patent 3½ years.

To all whom it may concern:

Be it known that I, SAMUEL N. ACKER, a citizen of the United States of America, residing at Washington, in the District of Columbia, have invented a new, original, and ornamental Design for a Medallion, Badge, Watch-Fob, or Similar Article, of which the following is a specification, reference being had to the accompanying drawing, forming part thereof.

In the drawings, Figure 1 is a view show-

ing the obverse of a medallion illustrating my new design, and Fig. 2 is a view showing the reverse of the same.

I claim:

The ornamental design for a medallion, badge, watch-fob or similar article, as shown.

SAMUEL N. ACKER.
